UNITED STATES PATENT OFFICE.

GEORGE HEGEMAN HART, OF WEST HARTFORD, CONNECTICUT.

ELECTRIC SWITCH.

Application filed January 17, 1925. Serial No. 3,198.

To all whom it may concern:

Be it known that I, GEORGE HEGEMAN HART, a citizen of the United States, and a resident of West Hartford, in the county of Hartford, State of Connecticut, have invented certain new and useful Improvements in Electric Switches, of which the following is a specification.

This invention relates to electric switches, 10 for instance, of the type having a plurality of terminals mounted on a base, a rotatable switch blade or blades, and means for rotating the switch blade or blades for throwing the same into and out of engagement with the terminals.

The invention relates, more particularly, 20 to the manner in which the terminals are associated with the base, and the aim of the invention is to provide an improved and novel arrangement by means of which the terminals are very effectively, economically and securely anchored to the base, the arrangement being such that each terminal cannot, in any way whatsoever, change its 25 relation to the base, the terminals being held against turning or canting movements in all directions.

Other objects will be in part obvious and in part pointed out more in detail hereinafter.

The invention accordingly consists in the features of construction, combination of elements and arrangements of parts which will be exemplified in the construction herein- 35 after set forth, and the scope of the application of which will be indicated in the appended claims.

In the accompanying drawings, wherein I have shown, for illustrative purposes, one embodiment which the present invention 40 may take, it being understood that this disclosure is by way of illustration only and that the invention is susceptible of various modifications and changes:

Figure 1 is a top plan view of the switch base and two terminals applied thereto;

Fig. 2 is a side elevational view of what is shown in Fig. 1;

Fig. 3 is a sectional view taken on line 50 3—3 of Fig. 1; and

Fig. 4 is a perspective view of one of the terminals.

Referring to the drawings in detail, a 55 designates a base of any suitable construction and formed of any desired insulating material, such as porcelain. This base, by

preference, is generally circular and has an upstanding flange provided with grooves or channels 10 in each of which is located a terminal designated generally by the letter 60 b. The number of grooves 10 will, of course, depend upon the type of switch and the number of terminals to be employed therein. In the present instance, the switch blade or 65 blades and the operating mechanism therefor are not shown, as the particular constructions thereof form no part of the present invention.

Each of the terminals, by preference, has a body or supporting member 12 to which is secured one or more contacts 13 of any 70 desired shape or type. By preference, the body portion 12 is in the form of a piece of metal bent to U shape and between the laterally extending arms of this member is secured the contact or contacts 13. The lower arm 14 of the member 12 has a tapped hole 15 into which is adapted to be screwed a screw 16 extending upwardly through the 75 bottom of the base. The upper arm 17 may also have a tapped hole 18 to receive a screw 19 by means of which the lead wires are 80 connected to the terminal.

In accordance with the present invention, 85 each terminal is provided with a pair of laterally extending and oppositely disposed ears or lugs, and the sides of the grooves 10 have recesses or depressions adapted to receive the respective lugs. In the present 90 illustrative disclosure, one of the arms, by preference the upper arm 17, is provided with such projections or lugs designated by the numeral 20, and the notches or recesses 95 which receive these grooves and which are designated by the numeral 21, are provided at each side of a groove 10 in the upper surface of the circular flange of the base. It will be noted from the drawings, that the lugs 20 fit more or less closely in the recesses or 100 notches 21 and are seated against the bottoms of these recesses. With this arrangement, it will be observed that the terminals are 105 very securely anchored in place and held against movement relative to the base in all directions. More particularly the terminals are held against a rotary movement and they are maintained by the interengaging lugs and recesses against canting or tilting laterally, all of which means that the contacts of 110 the terminals will be held at all times very rigidly in proper alignment with the switch blade or blades.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

1. In an electric switch and in combination, a base provided with a groove having

at its upper end and at each side a recess, 20 a terminal mounted in said groove and having on opposite sides laterally extending projections fitting in said recesses, and means securing the lower end of said terminal to said base.

2. In an electric switch and in combination, a base provided with a groove having at its upper end and at each side a recess, 25 a terminal located in said groove and including a U-shaped body member and a contact secured thereto, the upper arm of said body member having laterally extending lugs on opposite sides engaging in said recess, and a screw extending upwardly through the base and threaded into the lower arm of said U-shaped member.

GEORGE HEGEMAN HART.
